UNITED STATES PATENT OFFICE.

HUGH L. McAVOY, OF BALTIMORE, MARYLAND.

IMPROVED APPARATUS FOR CARBURETING AIR.

Specification forming part of Letters Patent No. 57,164, dated August 14, 1866.

To all whom it may concern:

Be it known that I, HUGH L. McAVOY, of Baltimore, in the county of Baltimore and State of Maryland, have made a new and useful Improvement in Air-Carbureting Machines; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a transverse vertical section through the center of the machine. Fig. 2 is a vertical transverse section of the regulator at its full height. Fig. 3 is a front elevation. Fig. 4 is a perspective view of a portion of the air-forcing wheel, showing the open end. Fig. 5 is a longitudinal vertical section of the machine. Fig. 6 is a side elevation.

The invention consists of a machine through which a body of air is forced by a motor, (weight, for instance,) and is caused to circulate against surfaces charged with hydrocarbon liquid for the purpose of carbureting it.

The peculiar features of the machine consist—

First, of an air-forcing cylinder or chamber revolving in a tank within a revolving carbureting-cylinder which revolves within the hydrocarbon reservoir and carries up a portion of hydrocarbon for exposure to the air which circulates through the machine.

Second, it also consists of a regulating-chamber so placed above the machine and operated by the influx of gas thereinto as to close the passage of gas from the machine and stop its operation till the pressure is relieved by removal of gas from the regulating-chamber.

Third, it also consists of a central displacing-chamber placed within the air-forcing chamber and provided with radial arms which connect it with the exterior case.

Fourth, the carbureting-cylinder provided with a reticulated or permeable surface, and with lifting cups or receptacles on its inside for dripping upon the air-forcing wheel.

Fifth, the semi-cylinder or chamber placed within the carbureting-cylinder occupied by the air-forcing wheel, separating the fluid in which the latter revolves from the hydrocarbon fluid in which the carbureting-cylinder revolves.

Sixth, the provision of hanging lamp-wick or analogous material within the air-forcing wheel when the latter revolves in hydrocarbon fluid.

In the drawings, A, Fig. 1, represents a cylinder or other shaped vessel of metal, closed at each end, and made perfectly air-tight by stuffing-boxes where the spindles pass through the ends, and supported upon a frame, *a a a a*. One of these spindles, *b'*, is shown having a pinion and train, *c' c''*, of wheels working in connection therewith to revolve the air-forcing wheel C, which is affixed to the spindle and revolves with it.

The air-forcing wheel C is provided with wings radiating from a central cylinder, *e*, which divide the space in the air-forcing wheel into sections of the required number.

At the upper edge, where joined to the periphery of the wheel, the radial arms are so arranged by bending as to make one side edge in advance of its opposite. To the outer edge of the radial arms there are soldered wings, extending from the center to periphery and equal in surface to the spaces between each pair of arms, one edge only being soldered to each arm, and its opposite being an inch or more at the periphery of the wheel from the arm to which it extends, as shown at Z, Fig. 5, and in the perspective view, Fig. 4. The end of the wheel nearest the gearing is closed by a metal disk or cover from center to periphery, soldered thereto and made air-tight.

The air-pipe *d*, Fig. 5, is a metal tube bent in the form therein seen, one end being soldered to the cover of the cylinder, and the other passing through the end of the cover of the wheel C up to near the periphery of the wheel. In the center of the air-pipe there is a thimble soldered for the spindle to pass through, as shown, and the cover of the wheel has an opening in the center large enough to revolve around the air-pipe.

The air-forcing wheel revolves within a cylindrical or other shaped chamber, B, which is soldered to the outside case A, and at the other end is supplied with a stuffing-box in the center, through which the spindle passes which revolves the air-forcing wheel C, making the chamber water-tight. The chamber B is filled with fluid gasoline or a heavier hydrocarbon, or with water.

The carbureting-drum D revolves upon a spindle, *d'*, which enters at one end the spindle revolving the air-forcing wheel, and at the

other passing through a stuffing-box on the outside case. The two spindles, arranged as seen in Fig. 5, passing through the stuffing-boxes, render them rigid and capable of supporting the wheel and carburete.

The carbureting-drum D is made of perforated metal or any frame-work, and may be covered with felt or other porous substance, or may have a reticulated or perforated surface, for the purpose of exposing a larger surface to the action of the vapor. This drum is provided with caps or receptacles on the inner surface to raise up and drip the hydrocarbon liquid upon the wheel C, and revolves in hydrocarbon fluid, while the air-forcing wheel revolves in separate fluid, and the two are arranged to revolve in the same or in opposite directions, and the drum, by separate gearing K l and link-band m, in connection with the spool I and cord and weight which give it motion, may have a faster or slower motion than the air-forcing wheel, or may be attached to the spindle b'.

The regulator F is a vessel of any shape, closed at each end, having a slot or opening, as seen in Figs. 1, 2, and 5, sufficiently wide to admit of the pipes G and H and the requisite play of the regulator from side to side, when supported upon a shaft connected with one edge of said slot, the shaft passing through a stuffing-box on one end of the close vessel E, which contains the regulator, and at the other resting in a box or journal within said vessel E.

The shaft, which supports the regulator F and is the fulcrum upon which it turns, has a small pulley-wheel, o, or lever on its outer end, which, by a band, operates upon a still smaller pulley, p, attached to a spindle, to which is connected the regulator-valve R within the pipe G.

The regulator-chamber E is filled with fluid, as shown, to any height which may be found most desirable, and has an outlet-opening on the top for the admission or escape of air.

There are suitable openings in the machine for filling or emptying each of the several parts with the fluid required, which will be easily understood.

The operation of the apparatus may be understood by supposing the air-forcing wheel-chamber B filled with fluid to just cover the air-tight or solid vessel c, the outer chamber, A, with hydrocarbon fluid to any height above or below the spindle which may be desired. The regulating-chamber is also supplied with fluid, as before explained. Weight being applied to the cord, the spool I, revolving, gives motion to the train of wheel-work connected with the air-forcing wheel C, which, drawing air from the action of its radial wings and propellers through the pipe d, forces it into the chamber A, when, by passing over and through the perforations in the drum D, it is thoroughly carbureted before passing through the pipe G into the regulator F, from whence it passes through the pipe H, to be used for

the purposes of illumination or otherwise. The action of the regulator may be understood by supposing it filled. By pressure of the air-forcing wheel it would be raised by turning on the fulcrum described, operating at the same time on the regulator-valve R to partially or wholly close the pipe G, through which the vapor passes into the chamber F. Upon the removal of the pressure within through escape of or consumption of the gas in the pipe H, the unequal balance of the regulator would cause it to fall to the position shown in Fig. 1, and the valve R would be again open fully for the admission of a further supply of vapor.

It will be also seen that when there is no escape going on through the pipe H there can be no motion of the air-forcing wheel, it being held stationary by the pressure within the chamber A and regulator F.

The spindles b' and d', Fig. 5, may be connected or revolved independently. In the former case the three stuffing-boxes described will be necessary, and the train of wheels c'' and c' from the spool I will be sufficient; but when disconnected the spindle d' will be rotated by the band m on the drums k l, and the middle stuffing-box may be dispensed with.

The drip from the cylinder keeps the chamber B sufficiently full to operate well when once started right. The chamber B may overflow into A without injury.

This apparatus may be used by the pressure of gas from the gas-main, instead of being revolved by mechanical appliances attached to the air-forcing wheel; or the two may work in unison.

What I claim as new, and desire to secure by Letters Patent, is—

1. The air-forcing chamber C, revolving in the tank B, which is surrounded by the reservoir A, in which the carbureting-cylinder or its equivalent revolves.
2. The inverted chamber F, vibrating upon the axis and actuated by the varying pressure of the gas contained therein, to operate as a regulator, substantially as described.
3. The displacing-chamber c in the chamber C', operating as described.
4. The carbureting-cylinder D, provided with cups or receptacles on its inner side, and with reticulated or permeable surface on its periphery.

5. The chamber B, containing the fluid in which the air-forcing cylinder revolves, and separating it from the fluid in the reservoir.

6. The hanging strands or tapes h' in the chamber C, as and for the purpose described.

To the above specification of an improved air-carbureting machine I have signed my hand.

HUGH L. McAVOY.
